UNITED STATES PATENT OFFICE.

ANDREW CEMAZAR, OF CROWEBURG, KANSAS.

DOOR-MOUNTING MECHANISM.

Application filed May 2, 1924. Serial No. 710,617.

To all whom it may concern:

Be it known that I, ANDREW CEMAZAR, a citizen of the United States, residing at Croweburg, in the county of Crawford and State of Kansas, have invented certain new and useful Improvements in Door-Mounting Mechanisms, of which the following is a specification.

This invention relates to door mounting mechanism, and particularly to a mounting mechanism having means for reversing the door pivots from one side of the door to the other.

An object of the invention is to provide a door structure, wherein the same is provided with socket members at each side thereof for receiving means adapted to be alternately projected from opposite sides of the door, so that the pivot connection for the door may be changed from one side thereof to the other, in order that the opening movement of the door may be effected from either side of the door jamb.

Another object of the invention resides in providing means in connection with the pivoting member of the door operating to prevent the retraction of the pivot members at one side of the door, before the projection of the member at the opposite side of the door, so that it is substantially impossible to retract both of the pivot members in the ordinary use of the door, and in changing the pivots one after the other, which would permit the door to be removed from the jamb.

Another object of the invention resides in providing a door structure including a jamb, wherein the door is provided with housings at each side, which movably mount a pair of rod members adapted to be projected in opposite directions beyond the ends of the door, for engagement with sockets in the jamb, so that the members in either housing may be projected for forming a pivot for the door, at either side thereof, means being provided for preventing the retraction of one pair of members in one housing, from pivotal connection with the sockets, until the other pair of members are projected into their corresponding sockets.

Another object of the invention resides in providing means which will prevent the retraction of one pair of bars from the sockets in the jamb, and will prevent the projection of the other pair of bars, when the door is swung to an open position.

The invention comprehends other objects and improvements in the details of construction, and arrangement of the parts, which are more particularly pointed out in the following description and claims, directed to a preferred form of the invention, it being understood, however, that various changes may be made in the construction and arrangement of the parts, within the scope of the invention as described and claimed.

In the drawings, forming a part of this application:

Figure 1 is a view of the door in closed position, which is equipped with the structure forming the subject of the present invention.

Figure 2 is an enlarged detail sectional view, with parts broken away, through the door, showing the elements of the mechanism in their respective positions.

Figure 3 is a plan view of the lock releasing mechanism for operation in connection with the bar members in one side of the door.

Fig. 4 is a plan view showing the lock releasing mechanism with portions broken away for clearness.

1 indicates the door, and 2 the door jamb, which includes the sill 3, and in which the door 1 is adapted for mounting for swinging movement from either side. The door is provided, at opposite sides, with housing members 4, which extend from end to end, as clearly illustrated in the drawing, to provide an enclosure within the side portion of the door for each mounting mechanism. The ends of each housing 4 are provided with guides 5, which slidably mount a pair of bar members 6 and 7 respectively. The upper bar member 6 of each housing, is provided at its lower end with an offset end portion 8, which is connected to the upper end of the lower bar member 7, through the medium of operating links 9, which are pivotally mounted, intermediate their ends as at 10, and have pin and slot connections as at 11, with the bar members 6 and 7 respectively, at the ends thereof. A suitable operating handle is provided at 12, for rotating the operating link 9, on the pivot 10, for sliding the bars in opposite directions, for either retraction or projection beyond the ends of the door. The upper or lower ends of the rods 6 and 7 are slidably mounted in openings 13, in the upper and lower ends

of the housing member 4, so that the rods are effectively guided in their sliding movement. Each of the lower rods 7 is provided with a rod extension 14, from the upper inner end which slide through bracket 15, between which, and the upper end of the rod 7 is mounted a coil spring 16 for normally projecting the rods beyond the ends of the door. The rods 7 are also provided with stops 17, adapted to engage the guides 5 for limiting the projecting movement of the rods. The upper rods 6 are provided with stops 18, which engage with the adjacent guides 5, for limiting the retracting movement of the rods in the housing member, in order to prevent the ends from being drawn entirely through the openings 13, in the ends of the housing members.

The sill 3 of the door jamb is provided at opposite ends thereof with socket members 19, arranged in line with the bar members 7 when the door is in closed position, so that the projection of these bar members beyond the lower ends of the housing members, will seat the same within the sockets 19, for a purpose which will presently appear.

The top portion of the jamb 2 of the door is provided with a chambered portion 20, closed at the lower side by plates 21, which are formed with openings 22, in line with the upper end of the rods 6 of the door, when in closed position, so that the end portions of these rods are adapted to be projected through the openings 22 of these plates. Each plate mounts a bearing member 23, which rotatably supports a releasing finger 24 of bell crank form, having one arm projected in line with the opening 22, and in the path of movement of the adjacent rod 6, while the other end of the releasing fingers is loosely pivoted to a rod 25, which extends through angle brackets 26, mounted on each plate. Between the angle brackets, the connecting rod 25 is provided with a pair of collars 27, which are adjustable relative to each other on the rod, and which are adapted for providing abutments for coil springs 28, which are interposed between the collars 27, on the one hand, and corresponding bracket members 26 on the other, so that a balancing action between the springs will result, which will normally tend to balance the operation of the releasing fingers.

Locking members are of spring material indicated at 29, and each is in the form of a rod slidably mounted in the bracket 26, in parallel spaced relation to the connecting rod 25, the end portion of which is offset downwardly as indicated at 30, and slidably operates between the bearing members 23, as clearly shown in Figure 3, so that the end is adapted for projection under predetermined conditions, to engage the recess 31,

in the end of the adjacent rod 6, when the same is projected beyond the end of the housing 4, and extended through the opening 22 of the respective plate 21, as clearly shown in Figure 2, so that an operation of the handle 12 will be prevented, for retracting the rods 6 and 7, until they and the opposite side of the door are projected so that the end of rods 7 will engage in the socket member 19, and the end of the rod 6 in the opening 22 for operating the releasing finger 24, for moving the locking rod 29, to disengage the end thereof from the recess 31, in the upper bar member 6, in the housing at the opposite end of the door. The locking bars 29, are operated simultaneously with the connecting bar 25, through connection with the collars 27, so that an operation of one of the releasing fingers 24, for rocking the bell crank on its pivot, and operating the connecting rod 25, will effect a similar operation of the locking bars 29, for releasing the rod at one side of the door, while the locking bar at the other side of the door will be projected toward the recess 31 of the other upper rod, for retaining said rod in the projected position.

Pawl 32 are pivoted at one end, in suitable brackets 33, carried at the upper ends of the housings 4, and are adapted for engagement at their lower free ends with projections 34, on the upper rods 6. Springs 35, mounted in the housings 4, are adapted to normally force the pawls 32, so as to engage with the upper portions of the upper rods 6, so that when the rods 6 and 7 are retracted within the housings, the pawls will ride into engagement with the projections 34, to prevent a subsequent projecting movement of the rods 6 and 7, by the operation of the handles 12. Each pawl 32 is provided, intermediate its ends with a release member 36, pivotally connected at one end thereto, and having the other end projecting through an opening 37, in the respective housing 4, and adapted for engagement with the respective jamb of the door.

From the above description, it will be seen that a door equipped with this invention, may be mounted, for swinging movement, from either side, by operating the handle 12 at the side which it is desired to pivot, for projecting the rods 6 and 7, beyond the upper and lower ends of the door, into the socket 19 and the opening 22, in the corresponding ends of the jamb, which action will be permitted, when the door is in closed position, by the respective pawl 32, as the releasing link 36 will be operated by engagement with the door jamb 2, to project the pawl inwardly out of engagement with the projection 34, so that the handle may be operated for moving the rods 6 and 7 to project the ends, the ends of the upper rod being moved through the

opening 22, engaging the releasing finger 24, and rocking the bell crank lever about its pivot, for sliding the connecting bar 25, toward the rod 6, being projected, so that the locking bar 29 will be correspondingly operated, in order to move the offset end 30, into engagement with the slot 31, in the ends of the rod 6, as the limit of the projecting movement is reached. When this end 30 has seated in the recess, it will be clear that further operation of the handle 12 will be ineffectual for operating the rods 6 and 7 respectively, as the locking member 29 holds the rods in projected position, so that the door may be swung on the projecting bars as a pivot or hinge. If it is now desired to move the pivot or hinge connection of the door to the other side, it will be necessary to close the door for the purpose of operating the connecting link 36 to release the pawl 32 from the projecting bar, which will permit the handle 12 to be operated, for projecting the rods 6 and 7 into the corresponding housing 4, which projection of the upper rod, through the opening 22 of the plate 21, will effect an operation on the other releasing finger 24, and cause the locking bar to be released from the recess in the other rod 6, so that the spring 16 in the extension portion of the lower rod 7 will operate to retract each of said rods 6 and 7 to their inner limits of movement, while the locking bar will engage the notch 31 of the other upper rod for effectively locking it in projected position, so that the door may be swung on the pivot at the opposite side, as desired.

It will, therefore, be clear, that a simple and efficient structure for mounting doors for swinging movement from either side, has been provided, which will effectively prevent the retraction of the pivot

members at one side, until the members at the other side have been projected, in order to prevent the detachment of the door from the jamb, under ordinary conditions, means being also provided for preventing the operation of the parts, while the door is in open position.

What is claimed is:

In combination, a door, a jamb, housing members mounted on each side of the door, a pair of oppositely movable rods slidably mounted in each housing, means for normally retracting said rods projecting beyond the ends of the housing, manually operable means for projecting said rods beyond the ends of the doors, sockets members carried by the jamb for receiving the projected ends of the rods, one of the socket members comprising an apertured plate mounted in the jamb, a chamber formed in the jamb adjacent said plate, bearing members mounted on the plate, releasing fingers pivotally mounted in said bearing members, in line with the ends of the rods, for engagement and operation thereby, connecting means between the releasing fingers for effecting the simultaneous operation thereof, and locking means operated by said releasing means, whereby the projection of the rods at one end will operate said releasing fingers for releasing the rods at the other end of the door, permitting the retraction thereof, and will operate the locking means for locking said projected rods in projected relation, said locking means preventing the retraction of said rods, until operation of the bar members at the opposite end of the door for projection into the socket members.

In testimony whereof I affix my signature.

ANDREW CEMAZAR.
